CLAIM

The ornamental design for a container sleeve, as shown and described.

DESCRIPTION

FIG. 1 is a first perspective view of the container sleeve;

FIG. 2 is a first side view thereof;

FIG. 3 is a second side view thereof;

FIG. 4 is a third side view thereof;

FIG. 5 is a fourth side thereof;

FIG. 6 is a top view thereof; and,

FIG. 7 is a bottom view thereof.

The broken lines in the drawings depict stitching lines and form no part of the claimed design.
